(57) **CLAIM**

The ornamental design for a dynamic light display tower, as shown and described.

DESCRIPTION

FIG. 1 is a front elevation view of a dynamic light display tower showing my new design;

FIG. 2 is a back elevation view thereof;

FIG. 3 is a top plan view thereof;

FIG. 4 is a bottom plan view thereof;

FIG. 5 is a right side elevation view thereof, the left side being a mirror image; and,

FIG. 6 is a perspective view thereof.

The translucent cover is shown in broken lines for illustrative purposes only and forms no part of the claimed design.
